UNITED STATES PATENT OFFICE.

BENJAMIN L. FRY, OF LOS ANGELES, CALIFORNIA, ASSIGNOR TO B. L. FRY MANUFACTURING COMPANY, OF ST. LOUIS, MISSOURI, A CORPORATION OF MISSOURI.

GRINDER.

1,100,722.

Specification of Letters Patent. Patented June 23, 1914.

Application filed May 24, 1913. Serial No. 769,623.

To all whom it may concern:

Be it known that I, BENJAMIN L. FRY, a citizen of the United States, residing at Los Angeles, in the county of Los Angeles and 5 State of California, have invented new and useful Improvements in Grinders, of which the following is a specification.

This invention has for its object the provision of a machine for domestic use for 10 sharpening knives, scissors and kindred edged implements or tools, the purpose being to provide a manually operable grinder involving a minimum number of parts and a simple construction.

15 The primary intention of the invention is the construction of a grinder embodying a vertical shaft, a grinding wheel secured to such shaft and arranged to rotate in a horizontal plane and support drive gearing embodying a pinion secured to the vertical shaft, and a drive gear of comparatively large diameter whereby the grinding wheel is caused to rotate at a comparatively high speed, which in practice gives the best results.

20 The invention consists of the novel features, details of construction and combination of parts, which hereinafter will be more particularly set forth, illustrated in the accompanying drawing, and pointed out in the appended claims.

25 Referring to the drawing, forming a part of the specification, Figure 1 is a side view of a grinder embodying the invention; Fig. 2 is a front view partly in section; Fig. 3 is a detail view of the guard or rest for the work.

30 Corresponding and like parts are referred to in the following description, and indicated in all the views of the drawing, by the same reference characters.

The frame of the machine comprises a clamp 1 and bracket 2, the latter extending upwardly from the upper jaw of the clamp 45 1 and having the outer end of its overhanging arm formed with a vertical opening to receive the shaft 3, which carries the grinding wheel 4. A collar or boss 5 is provided upon the upper side of the overhanging arm 50 of the bracket 2 and receives the work rest or guard which is mounted to turn thereon. The shaft 3 is stepped at its lower end in the upper jaw of the clamp 1 and its upper portion obtains a bearing in the overhanging arm 55 and the collar 5 of the bracket 2. A

stop collar 6 is pinned or otherwise secured to the shaft 3 and engages the under side of the overhanging arm of the bracket 2 and prevents vertical movement of the shaft. A pinion 7 is secured to the lower end of the 60 shaft 3 near the clamp and meshes with a drive gear 8, which is mounted upon an axle 9 let into the upright member of the clamp 1, said drive gear being provided with a handle for manual operation. 65

The guard or rest for the work comprises a horizontal bar 10 and uprights 11, the latter being equally spaced from the edge of the grinding wheel 4 and located at diametrically opposite points. The upper ends of 70 the uprights 11 project above the grinding wheel and are beveled, as indicated at 12, to give proper inclination to scissors or shears when sharpening the same. The bar 10 is provided at a central point with an eye 13, 75 which is of a diameter to snugly receive the collar or boss 5 upon which the guard or rest is mounted to turn. A set screw 14 is threaded into an opening formed in a side of the eye 13 and its inner end is adapted to 80 engage the collar or boss 5 to hold the guard or rest in the required adjusted position.

In the use of the machine the knife blade to be sharpened is introduced into the space formed between the edge of the grinding 85 wheel and an upright 11 with its back resting upon the horizontal bar 10. The blade is tilted to throw the edge against the edge of the wheel and with the back of the blade against the upright 11. In this position the blade is moved longitudinally upon the bar 10 to bring every portion of its edge in contact with the grinding wheel. After the blade is ground upon one side it is reversed to the opposite side of the grinding wheel 90 and the operation is repeated, thereby grinding both sides of the blade, with the result that a keen edge is produced. The grinding or sharpening of the blade may be finished upon the upper side of the grinding wheel. When it is required to sharpen a pair of scissors or shears the blade is placed with its edge upon the top of the grinding wheel and with the blade against the beveled portion 12 of an upright 11. By having 95 the guard or rest for the work mounted in the manner hereinbefore stated it may be adjusted to the most convenient position and when so adjusted is made secure by means of the set screw 14. 100 105 110

- From the foregoing description, taken in connection with the accompanying drawing, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the claims appended hereto.
- Having thus described the invention what is claimed as new, is:—
1. A grinding wheel comprising a frame having a projecting collar or boss, a shaft mounted in the frame, a grinding wheel secured to the projecting end of the shaft, means for imparting rotary movement to the grinding wheel, a bar having an eye intermediate of its ends to snugly receive the before mentioned collar or boss, and uprights at the ends of the bar extending along opposite edges of the grinding wheel and spaced therefrom.
  2. A grinder comprising a frame embody-

ing a clamp and bracket, the latter having an overhanging arm upon the upper side of which is formed a projecting collar or boss, a vertical shaft mounted in the clamp and overhanging arm of the bracket, means for preventing vertical displacement of the shaft, a grinding wheel secured to the upper end of the shaft, a pinion made fast to the lower portion of the shaft, a drive gear mounted upon the clamp and having its teeth in mesh with the pinion, a work rest comprising a horizontal bar having an eye at a central point mounted upon the collar or boss of the bracket, and uprights at the ends of the bar extending along the edges of the grinding wheel and having their upper ends projecting above the plane of the grinding wheel and beveled, and a set screw threaded into the eye of the horizontal bar to secure the work rest in the adjusted position.

In testimony whereof I affix my signature in presence of two witnesses.

BENJAMIN L. FRY.
